ABSTRACT OF THE DISCLOSURE

The honing assembly comprises a hollow head or shell provided with a plurality of circumferentially spaced slots, honing elements projecting from the slots, and an adjusting member for the honing elements within the head. The honing elements are seated in grooves in the adjusting member, and carrier blocks mounted on the adjusting member alongside the grooves support spring pressed balls which frictionally engage the honing elements to retain them in radially adjusted position.

BACKGROUND OF THE INVENTION

This invention is an improvement on prior constructions in which the honing elements are prevented from falling out of the slots by having a tight fit in the slots.

SUMMARY OF THE INVENTION

It is an essential object of this invention to provide a honing assembly having means for holding the honing elements in adjusted position.

Another object is to provide a honing assembly comprising a head having an adjusting member therewithin for radially adjusting a plurality of honing elements projecting through slots in the head, including means carried by the adjusting member for frictionally holding the honing elements in radially adjusted position.

Another object is to provide spring-pressed members frictionally contacting the honing elements to hold them in radially adjusted position.

Another object is to provide a retainer for each of the honing elements, the retainer including a carrier block having a plurality of spring-pressed balls urged into frictional contact with the side of the honing element.

Another object is to provide an elongated groove or recess in the side of each honing element to be engaged by the spring-pressed balls.

Other objects and features of the invention will become apparent as the following description proceeds, especially when taken in conjunction with the accompanying drawings wherein:

FIGURE 1 is a side elevational view, with parts broken away and in section, showing a honing assembly constructed in accordance with my invention.

FIGURE 2 is a side elevational view of a portion of the assembly shown in FIGURE 1.

FIGURE 3 is a sectional view taken along the line 3—3 of FIGURE 1.

FIGURE 4 is an enlarged fragmentary sectional view taken along the line 4—4 of FIGURE 1.

FIGURE 5 is an elevational view, with parts broken away and in section, of the adjusting member.

FIGURE 6 is a sectional view taken along the line 6—6 of FIGURE 5.

FIGURE 7 is a front elevation of a honing element retainer.

FIGURE 8 is a side elevational view of the honing element retainer shown in FIGURE 7.

Referring now more particularly to the drawings, the honing assembly or tool is generally designated 10 and comprises an elongated tubular head or shell 12, a plurality of honing elements 14 and an adjusting member 18.

2

The head 12 has a smooth cylindrical inner surface 20 for axially slidably supporting the adjusting member 18. Near its lower end the head 12 has a plurality of elongated, equally circumferentially spaced slots 16 which in the present instance are shown as extending axially of the head. A honing element 14 projects through each of the slots 16.

The honing elements 14 may be of any suitable construction and in the present instance are shown as comprising an elongated abrasive element or stone 22 of rectangular cross section mounted in a holder 24. The holder 24 may be of any suitable material such, for example, as metal or plastic. The front working face 26 of the stone 22 as well as one side are exposed, but preferably the other side and both ends of the stone are covered by the material of the holder. The rear surface or base 28 of the holder is inclined longitudinally of the honing element as indicated in FIGURE 1.

The adjusting member 18 is in the form of a cylindrical body having a plurality of elongated circumferentially spaced axially extending grooves 30 in its outer surface. The grooves extend from near the upper end of the adjusting member to the lower end thereof and respectively register with the slots 16 in the head. The base 32 of each groove is inclined axially at the same angle as the base 28 of the honing elements 14. The sides of each groove 30 are parallel to one another and to the longitudinal axis of the adjusting member, to closely receive and confine the opposite parallel sides of the honing elements.

The radially inner portions of the honing elements 14 are respectively received in the grooves 30 with the bases 28 of the honing elements flush against the bases 32 of the grooves. It will be obvious that a downward movement of the adjusting member 18 will result in radially outward adjustment of the honing elements 14. Any suitable means may be provided for axially raising and lowering the adjusting member 18 relative to the head. As shown in FIGURE 1, a rod 34 is connected to the upper end of the adjusting member 18 and extends axially upward through an opening 36 in the upper end of the head, having a coupling 38 at its upper end adapted to be joined to a suitable device for raising and lowering the adjusting member.

A honing element retainer 40 is provided for each honing element. Each retainer 40 comprises an elongated carrier block 42 and a plurality of spring-pressed balls 44. The carrier blocks are mounted in recesses 46 in the outer cylindrical surface of the adjusting member alongside each of the grooves 30. The recesses 46 are of the same size and shape as the retainers, as will be clear from FIGURES 5 and 7, and each has a side opening through one side of the associated groove 30. The carrier blocks 42 may be radially inwardly inserted into the recesses 46, and removably secured in position by fasteners 48.

The balls 44 are supported by the carrier blocks 42 in bores 50. The bores 50 extend transversely through the carrier block as shown in FIGURE 4, being open at both ends and, when the carrier blocks are mounted on the adjusting member, such bores extend chordwise thereof. The ends of the bores 50 which open into the grooves 30 are swaged over as indicated at 52 to provide a reduced opening of smaller diameter than the balls so that the balls cannot drop out when not in engagement with a honing element. The opposite ends of the bores are closed by the side 54 of the recess 46. Compression coil springs 55 in the bores bear against the side 54 of the recesses and constantly urge the balls 44 in a direction toward the grooves 30 so as to project partially into the grooves as shown in FIGURES 4.

The honing elements 14 preferably have an elongated groove or recess 58 in the side facing the retaining devices

40, into which the balls 44 are adapted to extend. As shown in FIGURE 1, the balls 44 of each retainer are arranged in a line at an inclination corresponding to and registering with the groove 58 in the associated honing element. The grooves 58 are parallel to the rear surfaces 28 of the honing elements.

In use, one or more balls 44 of each retaining device frictionally engage the groove or recess 58 of the associated honing element to frictionally retain it in radially adjusted position. The balls 44 may actually press the honing elements toward and into frictional contact with the opposite sides of the slots 30. Hence, the honing elements will not fly out of their slots by centrifugal force during rotation of the head after the head has been withdrawn from a cylindrical bore being honed. The balls 44 will frictionally retain the honing elements against the action of such centrifugal force.

When it is desired to adjust the honing elements radially outwardly, the adjusting member 18 is lowered camming the honing elements in an outward direction and causing the balls 44 to move downward in the grooves 58 of the honing elements. However, the balls continue to engage the grooves 58 and frictionally retain the honing elements in adjusted position. The engagement of the balls 44 in the grooves 58 will also pull the honing elements in a radially inward direction when the adjusting member is raised.

While it is preferred that the honing elements have grooves 58 for engagement by the balls 44, in a broader sense these grooves may be omitted and instead the balls may engage the flat side face of the honing elements to frictionally retain them in adjusted position.

In prior constructions, the honing elements have been held in the slots by having a tight fit in the slots. However, this resulted in slot wear to the point that the honing elements were no longer held by friction contact with the slot walls. Thus it became necessary to frequently replace the head. Moreover, reliance upon a tight fit in the slots made it difficult to install the honing elements in the slots without damaging the honing elements. A further disadvantage was inherent in this prior construction in that it afforded no means for retracting the honing elements.

In accordance with the construction herein described, the slots 16 are not subjected to wear since they may be slightly larger than the honing element because the honing elements are held in adjusted position by the retainers 40. Thus slot wear is no problem and the honing head lasts longer. Moreover, there is no problem connected with the insertion of the honing elements into the honing head through the slots. During this radially inward movement of the honing elements, the balls 34 are cammed back and then snapped into the grooves 58 in the sides of the honing elements. In addition, when the adjusting member 18 is raised, the balls cause the honing elements to be retracted radially inwardly. Hence the retracted honing elements will not bump the workpiece when the head is inserted in a bore to be honed.

What I claim as my invention is:

1. A honing assembly comprising a hollow head provided with a plurality of circumferentially spaced slots, honing elements adapted to project from said slots, an adjusting member for said honing elements supported within said head, and means carried by said adjusting member for resisting radial movement of said honing elements from adjusted position, said means including a plurality of balls, and a spring urging each ball laterally into contact with one side of a honing element.

2. The honing assembly defined in claim 1, wherein each honing element has a recess receiving a ball.

3. A honing assembly comprising a hollow head provided with a plurality of circumferentially spaced slots, honing elements adapted to project from said slots, an

adjusting member for said honing elements supported within said head, and means on said adjusting member for resisting radial movement of said honing elements from adjusted position, said means including a surface of said adjusting member supporting a side of each honing element, a plurality of balls, and a spring urging each of said balls into contact with the other side of each of said respective honing elements, whereby to press the first-mentioned sides of said honing elements into friction contact with said surfaces of said adjusting member.

4. A honing assembly comprising a hollow head provided with a plurality of circumferentially spaced slots, honing elements adapted to project from said slots, an adjusting member for said honing elements supported for axial movement within said head, said adjusting member having a plurality of circumferentially spaced axially extending grooves respectively registering with said slots and receiving said honing elements, the bases of said grooves being tapered so as to move said honing elements radially outward in response to axial movement of said adjusting member in one direction, and means carried by said adjusting member adjacent each groove for resisting radial movement of the honing element in the latter groove from adjusted position, said means adjacent each groove including a ball, and a spring urging each ball laterally into contact with the associated honing element.

5. A honing assembly comprising a hollow head provided with a plurality of circumferentially spaced slots, honing elements adapted to project from said slots, an adjusting member for said honing elements supported for axial movement within said head, said adjusting member having a plurality of circumferentially spaced axially extending grooves respectively registering with said slots and receiving said honing elements, the bases of said grooves being tapered so as to move said honing elements radially outward in response to axial movement of said adjusting member in one direction, and means carried by said adjusting member adjacent each groove for resisting radial movement of the honing element in the latter groove from adjusted position, said means adjacent each groove including a carrier removably mounted on said adjusting member in a side wall of said groove and having a plurality of transverse bores opening into said groove, balls respectively slidably disposed in said bores, and springs in said bores urging said balls transversely so as to project from said bores and have contact with the associated honing element.

6. The honing assembly defined in claim 5, wherein said balls press said honing elements into friction contact with the side walls of said grooves opposite the first-mentioned side walls thereof.

7. The honing assembly defined in claim 5, wherein each honing element has an elongated groove parallel to the base of the groove in said adjusting member in which it is received, said balls engaging in said last-mentioned grooves.

8. The honing element defined in claim 5, wherein means are provided for positively preventing said balls from dropping out of said bores through the open ends thereof.
